GLOW DISCHARGE TUBE

Hirsch Epstein, Chicago, Ill., assignor of twenty-five per cent to Morris L. Epstein and twenty-five per cent to Bernard Epstein, Chicago, Ill.

Application June 22, 1931, Serial No. 545,384

10 Claims. (Cl. 176—14)

This invention relates to glow discharge devices of the general type known as "neon" signs although it is not limited to such devices as employ neon gas particularly. The invention is primarily concerned with the type of tubing used, which tubing produces highly favorable and distinctly new and unobvious effects in a device of this class. The tubing is also believed to be new per se and also constitutes the subject of the present invention.

Consider a neon tube sign of the ordinary type, for illustrative purposes. This sign comprises a transparent glass tube bent to the proper configuration and filled with neon gas to a predetermined pressure so that when current is made to flow through the tube a luminous glow is produced. Since the gas and the tube are both colorless, the sign is not visible, or is only barely visible, when no current is flowing through the same, as during the day time. It is an object of the present invention to improve the conspicuity of a sign of this kind at times when it does not carry current, without at the same time detracting from its appearance when it does carry current.

It is a further object of the present invention to increase the intensity of illumination produced by signs of this kind. Part of the light that is produced goes through the front of the tube and is therefore useful for the purposes intended. About half of the light however passes through the back of the tube and is wasted. It is one of the objects of the present invention to provide a tube of this kind with some arrangement whereby at least a portion of the light which heretofore was wasted through the back of the tube will be directed through the front of the tube thereby increasing the amount of light that would otherwise pass through the front of the tube.

In order to render the tube or sign more conspicuous at daytime I make the back of the tube of colored glass, and in order to increase the amount of light that is directed forward when current flows through the tube I make the coloring such as to reflect some of the light which strikes back of the tube. A tube wherein a portion at least is colored is by far more conspicuous than is a transparent tube and will stand out distinctly at daytime. The tube is not colored throughout because such coloring, although permitting light to pass through it, would necessarily shut off some of the light which is otherwise emitted from the tube when the same has current flowing through it.

It is a further object of the present invention to provide a sign of the above character wherein the backing may be of various colors in order to produce pleasing effects when the tube is illuminated. If the backing is of the same color as the color of the light emitted by the glow discharge it will materially increase the intensity of illumination of the device when viewed from the front. If the color of the backing is different from the color of the light emitted by the glow discharge of the particular tube then a two color effect is produced which is of striking appearance and readily attracts the attention of an observer. Such tubing is also more readable when the sun strikes it. The backing may be of two or more different colors which gives the tube a multi-color effect.

In connection with neon tube signs it has been observed that the light appears to emanate from a thin pencil or ribbon of light within the tube. When illuminated such tubes appear to be of appreciably smaller diameter than their actual diameter. By my invention the apparent diameter of a neon tube is increased as compared to the apparent diameter of a similar sized tube heretofore used. This is due to the colored backing of my tube.

In accordance with the teachings of my invention the colored backing of the tube may be formed in any one of a plurality of different ways. By way of example, the tube may be formed of two different pieces of glass one of which is colorless and the other is colored. Such glass may be formed into a tube in manners well known in the art. The advantage of colored glass over paint is that paint must be removed before repumping of the tube since paint carbonizes. I may also make the back of the tube of laminated construction and interpose the coloring material between the laminae. This latter arrangement offers the possibility of using a phosphorescent chemical for the coloring matter so that the material will become phosphorescent when the current is turned off. Some phosphorescent materials are activated only by ultra-violet light and where such chemicals are used I prefer to use a tube made of glass which is itself transparent to ultra-violet light so that the ultra-violet rays produced by the glow discharge may activate the phosphorescent material. Ultra-violet light is produced if the tube contains mercury vapor. Luminous calcium sulphide represents one suitable phosphorescent substance that is activated by ultra-violet light. This is merely one of a large and well known class of

phosphorescent substances any one of which may be used without departing from the spirit or scope of the present invention. If desirable the phosphorescent substance may be coated on the inner back side of the tube or it may be coated on the outer back side of the tube and then protected by a suitable outer layer of paint, lacquer, paper, or the like. When the phosphorescent substance is on the inside of the tube a tube of ordinary glass may be used whereas if it is on the outside of the tube then the glass of the tube must be transparent to ultra-violet light if the phosphorescent substance used is one of the kind that must receive ultra-violet light in order to be activated.

In the ordinary usage of my invention I contemplate arranging the coloring matter in strips extending longitudinally of the glass tube. The coloring matter would then be entirely on the back side of the tube and may extend for half of the circumference of the tube or slightly more or less than half of the circumference of the tube. For certain decorative effects the colored strips may be arranged spirally on the tube and may comprise one or more spirals of different colored glass. For other striking effects the glass tube may comprise alternate circles or collars of different colored glass.

The attainment of the above and further objects of the present invention will be apparent from the following specification taken in conjunction with the accompanying drawing forming a part thereof.

In the drawing:

Figure 1 is a front view of a portion of a representative glow discharge sign constructed in accordance with my invention, three of the letters of the alphabet being indicated;

Figure 2 represents a cross section of the tubing comprising the sign shown in Figure 1;

Figures 3 to 7 inclusive, represent cross sections of various different forms of tubing which may be used in a sign such as is shown in Figure 1;

Figure 8 is a fragmentary longitudinal view of a modified form of glass tube wherein the coloring is arranged in a spiral;

Figure 9 shows a still different form of tube wherein the coloring comprises a plurality of spirals; and

Figure 10 is a longitudinal view of a modified form of tube wherein the coloring comprises collars of different color of glass.

Reference may now be had more particularly to Figure 1. I have there shown a number of letters of a glow discharge sign. This is merely illustrative and comprises three letters of the alphabet indicated at 1, 2, and 3, and a decorative portion indicated at 4. This glow discharge sign may be one of the kind commonly known as neon signs and comprises glass tubing of substantially uniform thickness bent to the proper configuration and filled with a suitable gas and a predetermined pressure. While neon gas is most commonly used such signs are not limited to the use of neon gas since there are many other gases which may be used, as is well known in the art. Suitable electrical connections 5 are provided for passing an electric current through the gases within the tube for producing a luminous glow which appears as a pencil of light extending lengthwise in the tube. This is all well known in the art and no further description thereof is deemed necessary at this time.

My glow discharge sign differs from similar

signs heretofore known in the type of glass used. In Figure 2 there is shown a cross section of a representative glass tubing of which the sign shown in Figure 1 is made. The front portion of the tube comprises a colorless piece of glass indicated at 10, the rear wall of which is provided with an indentation into which is fitted another piece of glass indicated at 11. The inner rear side 13 of the tube may be integral with the front portion 10. Between the inner portion 13 and the outer portion 11 there is placed some coloring pigment 14. The glass portion 11 is intimately united with the portion 10 at the meeting lines so as to form one continuous tube therewith. In effect the portions 11 and 13 comprise two laminae with pigment 14 interposed between them. The strip 11 extends longitudinally of the tube and, in this form of my invention, is free of any helical twist. The tube shown in Figure 2 may be made by extruding the material through suitable dies to form a tube with an indentation on the outer back side for receiving the portion 11. The pigment may then be applied and thereafter the portion 11 united with the rest of the tube by extruding the same through suitable dies. It may also be made by first forming the laminae 11 and 13 as two separate pieces or strips, interposing the pigment between them, and then uniting those pieces with a front portion such as the portion 10, which front portion would of course be initially devoid of a portion such as the portion 13 shown integral with the portion 10. It is, of course, to be understood that the above statements as to how the tube may be made are not the essence of the present invention, it being understood that the tube may be made by any other desirable or preferred method.

The pigment material 14 may comprise a phosphorescent substance or a substance which becomes phosphorescent when it has been exposed to the action of light, or of ultra-violet light. If the substance used is one that requires activation by ultra-violet light then the parts used, or at least that portion of glass indicated at 13, should be of the kind transparent to ultra-violet light. Quartz glass is one such suitable glass and there are others known in the art. The front glass portion 10 is colorless whereas the rear portion 11 may be either colorless or colored glass. While I have shown the lines 15—15 which represent the juncture between the portion 11 and the portion 10 it is to be understood that when these portions are actually joined the glass flows together so that such lines are not visible in the finished product.

In the tube indicated in section in Figure 2, the colorless front portion of the tube extends for somewhat more than 180° of the periphery. In the modification shown in Figure 3 this portion extends exactly 180° and in the modification illustrated in section in Figure 4 this colorless front portion extends for somewhat less than 180°. Similar parts in Figures 2, 3, and 4 have been indicated by similar reference numerals, the reference numerals in Figure 3 being primed and the reference numerals in Figure 4 being given a double prime notation. In other respects the modifications shown in Figures 3 and 4 are identical to that shown in Figure 2.

The coloring material 14, whether it be of a phosphorescent substance or not, renders the same by far more visible at daytime when it is not illuminated than are corresponding signs which are made of a single piece of colorless glass. In addition, some of the light which would ordi-

narily pass through the back wall of the tube and be wasted is now reflected forward and serves to increase the intensity of illumination at the front of the tube. There is another and quite distinct 5 advantage in having the coloring matter 14. In glow discharge devices employing glass tubing colorless throughout, the glow appears to emanate from a narrow pencil or ribbon of light. When viewed at even a slight distance such a tube appears to be of the diameter of the ribbon of light. This is appreciably less than the actual diameter 10 of the tube. In glow discharge devices constructed in accordance with the teachings of my present invention, the light appears to emanate 15 from the entire tube and as a result the lighted tube appears of a larger diameter than the appearance of a similar tube without the coloring or pigment.

In Figure 5, I have illustrated a section of a 20 form of tubing which differs from that of Figure 4 in that two different colored pigments are used. The two different colored portions are indicated at 14a and 14b respectively. The coloring material of 14a may be red and the coloring material of 14b blue, although any other colors may be used. These different pigments may both be of 25 phosphorescent material or only one or the other may be phosphorescent, or neither may be phosphorescent. In other respects this tube is the 30 same as that shown in Figure 4. The showing in Figure 5 is merely illustrative and as such it has been shown in connection with the tube wherein the coloring portion extends for slightly more than half way around the tube, as in Figure 4. It 35 is however to be understood that the arrangement shown in Figure 5 may be arranged so that the coloring matter extends for just 180° of the periphery of the tube, as in Figure 3, or for somewhat less than 180° of the periphery of the tube, 40 as in Figure 2.

In Figure 6, I have shown a cross section of still another form of tube. This tube comprises 45 two pieces of glass 20 and 21 united to form a seamless tube. While I have herein shown the meeting edges of these two segments at 22 and 23 respectively, it is to be understood that when the two glass portions are united they merge or melt 50 into one another and no line of demarcation between them may be seen. The portion 20 represents the front portion of the sign and the portion 21 the rear part of the sign. The portion 21 is of colored glass, being of any desired color, such as red, yellow, green, blue, or violet. The portion 20 is of colorless glass. While I have 55 herein illustrated the colored portion 21 as extending for somewhat less than 180° of the periphery of the tube this may be departed from as in Figure 3 so that the colored portion extends just 180°, or for somewhat more than 180° of the periphery of the tube. The colored glass used is 60 preferably transparent, although opaque glass may be used.

The forms of my invention illustrated in Figure 6 may be further departed from by using two 65 different colored portions 21 and 21' in the manner indicated at 14a and 14b of Figure 5.

In Figure 7 I show a cross section of a tubing 70 wherein the front portion comprises a red glass section 26, a colorless section 27, and a blue section 28. The rear portion may be colorless and provided with a forward light directing reflector 29. This glow discharge tube may employ helium 75 gas, which emits a white light. The front of the tube therefore appears as red, white, and blue when illuminated.

In the forms of tubing illustrated in Figures 2 to 7 inclusive, the colored portion extends longitudinally of the tube. The invention is however not limited to this arrangement since the same may be arranged in the form of a spiral, as indicated in Figures 8 and 9 or in any other form. In Figure 8 the colorless portion of the glass is indicated at 30 and the colored portion is indicated at 31 both portions extending in spiral form.

The glass tube indicated in Figure 9 has three 10 spirals, namely the spirals 35 and 36 of different colors such as red and blue and the spiral 37 of colorless glass. Any number of different colors may be thus spiraled around in tubular formation.

In Figure 10 I have shown a tube wherein the 15 various colored portions indicated at 40 and 41 are arranged in collar formation and spaced apart by colorless portions 42. Various colored effect may be produced in this manner.

When using a backing of a single color the color 20 chosen may be the same as that of the light emitted by the particular tube. For instance, if the gas used for producing the glow is neon, which produces a red light, a red backing may be used. Blue, green, and yellow discharges are produced 25 by different gases and in those arrangements the backing would be made of a corresponding color. Where a contrast or a different effect is desired the color of the backing may be chosen to be different from the color of the light emitted by 30 the particular gas used in the glow discharge device. Likewise by using backing of two different colors a two color effect is given to the light emitted by the discharge tube.

The term "glass" has been here used in its 35 broadest aspect and is intended to cover all substances capable of being worked to produce a glass-like colorless and rigid tube.

In compliance with the requirement of the patent statutes I have herein shown and described a 40 few preferred forms of my invention. It is however to be understood that the invention is not limited to those precise forms, the same being merely illustrative of the broad principles of my invention. What I consider new and desire to 45 secure by Letters Patent is:

1. A glow discharge sign comprising a glass tube of a plurality of strips of different colored glass twisted in helical formation, and means for passing an electric current through the tube. 50

2. A glow discharge sign comprising a long and comparatively narrow glass tube of substantially circular cross section bent into shape to constitute the sign and characterized in that the rear side of the glass tube is colored and of a 55 color visible from the front side and the front side is of a plurality of different colors.

3. A glow discharge sign comprising a long and comparatively narrow glass tube bent to constitute a letter of the alphabet and containing a 60 conducting gaseous atmosphere and having means for passing an electric current therethrough, characterized in that the rear side of the tube is colored and of a color visible from the front side, said coloring being free of electrostatic action on the device and the front side of the tube being of a plurality of different colors. 65

4. A glow discharge device comprising a single walled glass tube with coloring matter interposed between the inner and outer surfaces of the wall of the tube, and means for passing an 70 electric current therethrough.

5. A glow discharge device comprising a glass tube with coloring matter interposed as a film 75

between the inner and outer surfaces thereof and extending spirally of the tube.

6. A glow discharge sign comprising a substantially circular glass tube defining a single circular chamber in cross-section, said chamber having a filling of gas of the type that produces a luminous glow of distinctive color upon the passage of an electric current therethrough, said tube being comparatively long in relation to its diameter and bent into shape so that the luminous glow extends longitudinally of the tube and constitutes the display portion of the sign, characterized by the fact that at least a substantial portion of the rear side of the tube is colored, and of a color visible from the front at the display portion of the tube and different from the color at the adjacent front portion of the tube, said coloring being interposed between the inner and the outer surfaces of the glass tube.
7. A glow discharge sign comprising a substantially cylindrical glass tube defining a single circular chamber in cross section, said chamber having a filling of gas of the type that produces a luminous glow of distinctive color upon the passage of an electric current therethrough, means for passing an electric current therethrough, said tube being comparatively long in relation to its diameter and bent into shape so that the luminous glow extends longitudinally of the tube and constitutes the display portion of the sign, characterized by the fact that the glass tube has a colored spiral formed thereon and of a color distinctly different from the characteristic color of the luminous glow produced by the gaseous filling, and pervious to the light of the glow discharge.
8. A glow discharge sign comprising a substantially cylindrical glass tube defining a single circular chamber in cross-section, said chamber having a filling of gas of the type that produces a luminous glow of distinctive color upon the passage of an electric current therethrough, means for passing an electric current therethrough, said tube being comparatively long in relation to its diameter and bent into shape so that the luminous glow extends longitudinally of the tube and constitutes the display portion of the sign, characterized by the fact that a substantial amount of the exposed part of a circular section of the tube

is colorless and a substantial amount of the exposed part of the same circular section of the tube is colored glass of a color distinctly different from the characteristic color of the glow produced by an electric discharge through the gas filling.

9. A glow discharge sign comprising a cylindrical single wall glass tube defining a single circular chamber in cross-section, said chamber having a filling of gas of the type that produces a luminous glow of distinctive color upon the passage of an electric current therethrough, means for passing an electric current through the tube, said tube being comparatively long in relation to its diameter and bent into shape so that the luminous glow extends longitudinally of the tube and constitutes the display portion of the sign, characterized by the fact that, in a transverse cross-section, a substantial amount of the exposed part of the tube is colorless glass and a substantial amount of the exposed part of the tube is colored glass, both the colorless and the colored portion of the tube being of transparent glass.

10. A glow discharge sign comprising a glass tube of glass of substantially uniform thickness bent into shape to constitute the display portion of the sign, said tube containing a gas of the type that produces a luminous glow of a distinctive color upon the passage of an electric current therethrough, means for passing an electric current through the gas within the tube for producing a luminous glow, the tube being comparatively long in relation to its diameter so that the glow constitutes a pencil of light of the shape of the display portion of the sign, the front of the tube being clear colorless transparent glass and the rear of the tube behind the colorless front portion being colored of the same distinctive color as that of the luminous glow, to reflect forward some of the light of the luminous glow, and also to reflect forward at least a substantial portion of extraneous light that may strike it when no electric current is passing through the tube, and the colored portion of the tube being also pervious to the light of the glow discharge whereby at least a fractional part of the light of the glow discharge passes through the back of the tube.

HIRSCH EPSTEIN.
